UNITED STATES PATENT OFFICE.

MORTON L. JOHNSON, OF CHICAGO, ILLINOIS, ASSIGNOR TO CORWIN TELEPHONE MANUFACTURING COMPANY, OF CHICAGO, ILLINOIS, A CORPORATION OF ILLINOIS.

TELEPHONY.

1,050,425.

Specification of Letters Patent. Patented Mar. 18, 1913.

Application filed May 22, 1911. Serial No. 628,770.

To all whom it may concern:

Be it known that I, MORTON L. JOHNSON, a citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to that class of telephone exchange systems in which telephone lines are automatically extended at an exchange, and while I have embodied my invention in an automatic telephone exchange system wherein calling telephone lines are automatically connected with called telephone lines, yet I do not limit myself to a system in which connection between calling and called subscribers is effected entirely by automatic operations at the exchange.

My invention has for its object the provision of improved means whereby a calling party at one of several stations upon a line, commonly known as party line stations, may appropriate his line to the exclusion of other stations upon the same line whereby such calling party may set the selecting mechanism at the exchange into operation without having the operation of such selecting mechanism interfere with other parties at the remaining stations upon the same party line.

In my application Serial No. 628,777, filed May 22, 1911, I have described a system for accomplishing the results above generally stated. In the equipment illustrated in said co-pending application I have shown a polarized magnet at each of the party line stations which is of very high resistance. These magnets are included in bridge of the party line and the circuit interrupting switch at each party line station is also included in bridge of the party line, for the purpose of operating the selecting mechanism at the exchange, the electro-magnets enabling a calling party to hold his own party line to the exclusion of other party line stations upon the same line.

In the system forming the subject matter of the present application I govern the operation of the selecting mechanism over a circuit which is distinct from or supplied in addition to the party telephone line circuit whereby I am enabled to simplify the con-

struction of the magnets and may also be able to reduce their resistance, owing to the fact that the circuit for the magnets and the circuit for governing the operation of the selecting mechanism are distinct.

I will explain my invention more fully by reference to the accompanying drawings showing an embodiment thereof in the form of an automatic telephone exchange system, to which the invention is not to be limited, 60 and in which drawings—

Figure 1 shows a party telephone line with four stations connected therewith, and Fig. 2 shows the exchange end of said party telephone line and automatically operated 70 selecting mechanism for effecting extension of the party telephone line.

The telephone line extends from the exchange to two limbs 1, 2 and, in the embodiment of the invention illustrated, is 75 normally connected at its side 2 with the negative pole of the grounded battery 3.

I have shown four party line stations A B C D though I do not limit myself to the number of stations that are connected 80 with the party line. As the invention is illustrated, the equipments at the four stations are identical except, if desired, the signal receivers at the different stations may be of harmonic type to respond to wave 85 form current of different periodicities to be selectively impressed upon the line at the exchange. The signal receivers may be alike, if desired, in which event code signals should be employed. Similar parts at the 90 different stations will be given similar characters of reference, one station being specifically described. In the system illus-

trated, being an automatic telephone exchange system, I have illustrated a well 95 known type of switching mechanism at each telephone station for operating the selecting mechanism at the exchange, this switching mechanism being slightly added to in order to accomplish the object of my invention. In the embodiment of the invention 100 illustrated, the switching mechanism is controlled by a well known dial mechanism that includes a spring winding finger ring or dial 4. The lever 5 engaged by the finger 105 at the limit of the dial stroke releases a spring actuated device that intermittently operates the circuit opening switch 6 during the return of the spring actuated mechanism to normal. The circuit which is inter-

110
115

rupted at 6 is established for interruption by a switch 6¹ that is closed after the switch 6² included in the telephone bridge is opened, the latter switch excluding the telephone outfit 10 and 14 from circuit so that the circuit for governing the operation of the selecting mechanism at the exchange is established independently of the telephone outfit, though I do not limit myself to this characteristic. The governing circuit mentioned has its switch 6¹ closed during the time the dial mechanism operates to open and close the switch 6. The governing circuit thus established at 6¹ during the circuit opening and closing operation of the dial may be traced from the grounded contact of the switch 6¹, the companion to such contact, the contacts of the switch 6, the contacts 7 and 8 of a master switch, the side 2 of the telephone line, the operating magnet 36 to the grounded battery, the side 1 of the telephone line, thus being excluded from the governing circuit. The telephone switch hook 9, when supporting the receiver 10, operates to depress the element 8 of the master switch, and there open the circuit through switch 6, through the intermediation of the depressing finger 11 and the right hand end portion of the lever 12 then depressed by the finger 11, this right hand end portion of the lever 12 being mechanically connected with the switching element 8 by means of a strut 13. The switch hook when depressed causes pawl 11¹ to hold the dial. There is a low resistance bridge conductor at each telephone station that includes the telephone transmitter 14 having one terminal telephonically connected with the limb 1 of the telephone line, the receiver 10 in serial relation with the transmitter 14, the dial switch 6, and the contacts 7 and 8. The normally open connection which has just been traced between the sides of the telephone line is in parallel relation with another bridge conductor which is desirably of high resistance and is preferably also open at the contacts 15, 16. This second bridge conductor includes a magnet 17 which is preferably non-polarized, and the entire resistance of this second bridge conductor is preferably located in the magnet 17 which may be wound, for example, to one thousand ohms resistance. The armature of the magnet 17 is preferably held in predetermined normal position by means of a spring 18 that normally locks the nose or angular extension 19 of the armature beneath the nose or angular extension 20 of the intermediately pivoted lever 12. A spring 21 normally presses the nose 20 against the nose 19. The contact element 16 is mechanically connected with the finger 11 so that said contact 16 is permitted to engage the contact 15 when the associated telephone receiver 10 at a calling station

is removed from its hook, whereby the high resistance bridge conductor including the magnet 17 is closed whereupon current from the battery 3 is permitted initial flow over the line sides to enable the magnet 17 to operate and draw its armature 19 from engagement with the nose 20 of the lever 12 against the force of the spring 18 whereupon the spring 21 is permitted to swing the lever 12 in a counter clockwise direction, the finger 11 having previously been raised owing to the removal of the telephone from its switch hook. The contacts 7 and 8 of the master switch are thereupon engaged, whereafter the previously traced circuit for governing the selecting mechanism is established at 6¹ by the operation of the calling party's dial and has its continuity intermittently broken at 6 in a manner which is well understood and for the purpose of operating the selecting mechanism at the exchange to extend the telephone line in a manner well known. During the impulse sending operation the side 1 of the telephone line is excluded from circuit as a consequence of the operation of the armature switch 39 and is attracted as a consequence of the establishment of circuit through the magnet 36 and the sluggishly acting relay 40, this latter relay establishing circuit through sluggishly acting magnet 41 that governs the armature switch 39, all as may readily be traced from the diagram, Fig. 2, the circuit for the magnet 40 being established through the armature switch of magnet 36 and the alternate contact of such armature switch while the circuit for magnet 41 is closed at the normal contact of the armature switch of relay 36, this contact being included in circuit with sufficient duration within the period of impulse sending to maintain the sluggishly acting magnet 41 energized, the circuit for the magnet 41 including the alternate contact of the lowermost armature switch of the sluggishly acting magnet 40. As a consequence of this the magnet 17 at a station late in seeking the line cannot be energized and therefore the telephone at this station cannot be included in circuit. The telephone at the station first taking the line, however, is included in circuit across the sides of the telephone line since at that time the operating magnet 36 has not been energized owing to the fact that the calling party does not operate his dial until after he removes his telephone from its switch hook. I also provide a pawl 11¹ that is normally held by the magnet to lock the dial so that the party at an intruding station cannot operate his dial whereby the line is further guarded, supplementing the guard effected at 7 and 8. In this way I have provided a simple circuit arrangement for enabling a calling party line subscriber

to appropriate his line to the exclusion of all other stations upon the same line.

If a party line subscriber is a called party such party may appropriate his line by simply removing his telephone from its switch hook whereupon a circuit is established through his magnet 17 that may be traced from the battery 3 through the upper winding through what is technically termed the "back bridge" relay 42 of the connector switch, the upper armature switch of the private relay 43, the armature switch 44 of the ringing relay 45, the connector wiper 46, the upper bank contact in engagement therewith, the alternate contact of the armature switch 47, the line side 2, the contact 8 and the contact immediately beneath the same, the contacts 15 and 16 at the called station, the magnet 17 at the called station, the line side 1, the lowermost armature switch 48 of the line switch, the alternate contact of such armature switch, the lower bank contact and the wiper 49 engaging the same, the armature switch 50 of the ringing relay 45 and the normal contact of such armature switch, the lowermost armature switch of the relay 43 and its contact, the lower coil of the magnet 42 to the battery. The line relay that includes the armature switches 47 and 48 forms a part of an ordinary line switch in automatic telephone equipment and whose armature is closed by a private wiper in a manner well known. The energization of the magnet at the called party line station permits the closure of the low resistance bridge through the telephonic apparatus at this station so that sufficient current is diverted from the magnet 17 at another station seeking the line to prevent this other magnet from operating whereby the dial mechanism at the intruding station is maintained locked and the master switch 7 8 is maintained open whereby the intruding party can neither operate his dial nor include his telephone in circuit relation with the line.

While I have herein shown and particularly described the preferred embodiment of the invention I do not wish to be limited to the precise details of construction shown as changes may readily be made without departing from the spirit of the invention, nor do I wish to be limited to a telephone exchange system that is purely automatic in its operation at the exchange.

Having thus described my invention, I claim as new and desire to secure by Letters Patent the following:

1. A telephone exchange system including a line connecting a plurality of telephone stations with an exchange; selecting mechanism at the exchange for extending the line therat; a circuit supplied in addition to the line circuit for governing the operation of the selecting mechanism; switching mecha-

nism at the telephone stations for operating the selecting mechanism over its governing circuit; electro-magnetic mechanism at the stations in bridge of the telephone line serving when deenergized to prevent the operation of the switching mechanism at the telephone stations and when energized to permit the operation of said switching mechanism, there being present switching devices at the telephone stations for establishing circuit through the electro-magnetic mechanism thereat; and means governed at a telephone station for rendering ineffective the circuit of the electro-magnetic mechanism at a companion telephone station.

2. A telephone exchange system including a line connecting a plurality of telephone stations with an exchange; selecting mechanism at the exchange for extending the line therat; a circuit supplied in addition to the line circuit for governing the operation of the selecting mechanism; switching mechanism at the telephone stations for operating the selecting mechanism over its governing circuit; electro-magnetic mechanism at the stations in bridge of the telephone line serving when deenergized to prevent the operation of the switching mechanism at the telephone stations and when energized to permit the operation of said switching mechanism, there being present switching devices at the telephone stations for establishing circuit through the electro-magnetic mechanism thereat; and means operated by the selecting mechanism when actuated in response to the switching mechanism at a calling station on said line for rendering ineffective the circuit of the electro-magnetic mechanism at a companion telephone station.

3. A telephone exchange system including a line connecting a plurality of telephone stations with an exchange; selecting mechanism at the exchange for extending the line therat; a circuit supplied in addition to the line circuit for governing the operation of the selecting mechanism; switching mechanism at the telephone stations for operating the selecting mechanism over its governing circuit; electro-magnetic mechanism at the stations in bridge of the telephone line serving when deenergized to prevent the inclusion of the telephones thereat in circuit with the line and when energized to permit the inclusion of the telephones thereat in circuit with the line, there being present switching devices at the telephone stations for establishing circuit through the electro-magnetic mechanism thereat; and means governed at a telephone station for rendering ineffective the circuit for electro-magnetic mechanism at a companion telephone station.

4. A telephone exchange system including a line connecting a plurality of telephone stations with an exchange; selecting mecha-

- nism at the exchange for extending the line thereat; a circuit supplied in addition to the line circuit for governing the operation of the selecting mechanism over its governing circuit; electro-magnetic mechanism at the stations in bridge of the telephone line serving when deenergized to prevent the inclusion of the telephones thereat in circuit with the line and when deenergized to permit the inclusion of the telephones thereat in circuit with the line, there being present switching devices at the telephone stations for establishing circuit through the electro-magnetic mechanism thereat; and means operated by the selecting mechanism when actuated in response to the switching mechanism at a calling station on said line for rendering ineffective the circuit of the electro-magnetic mechanism at a companion telephone station.
5. A telephone exchange system including a line connecting a plurality of telephone stations with an exchange; selecting mechanism at the exchange for extending the line thereat; a circuit supplied in addition to the line circuit for governing the operation of the selecting mechanism; switching mechanism at the telephone stations for operating the selecting mechanism over its governing circuit; electro-magnetic mechanism at the stations in bridge of the telephone line serving when deenergized to prevent the inclusion of the telephone thereat in circuit with the line and when energized to permit the inclusion of the telephones thereat in circuit with the line, there being present switching devices at the telephone stations for establishing circuit through the electro-magnetic mechanism thereat; and means governed by the telephone station switching mechanism serving to operate the selecting mechanism for rendering ineffective the circuit for electro-magnetic mechanism at a companion telephone station.
10. A telephone exchange system including a line connecting a plurality of telephone stations with an exchange; selecting mechanism at the exchange for extending the line thereat; a circuit supplied in addition to the line circuit for governing the operation of the selecting mechanism; switching mechanism at the telephone stations for operating the selecting mechanism over its governing circuit; electro-magnetic mechanism at the stations in bridge of the telephone line serving when deenergized to prevent the operation of the switching mechanism at the telephone stations and when energized to permit the operation of said switching mechanism, there being present switching devices at the telephone stations for establishing circuit through the electro-magnetic mechanism

thereat; and means governed by the telephone station switching mechanism serving to operate the selecting mechanism for rendering ineffective the circuit of the electro-magnetic mechanism at a companion telephone station.

6. A telephone exchange system including a line connecting a plurality of telephone stations with an exchange; selecting mechanism at the exchange for extending the line thereat; a circuit supplied in addition to the line circuit for governing the operation of the selecting mechanism; switching mechanism at the telephone stations for operating the selecting mechanism over its governing circuit; electro-magnetic mechanism at the stations in bridge of the telephone line serving when deenergized to prevent the inclusion of the telephone thereat in circuit with the line and when energized to permit the inclusion of the telephones thereat in circuit with the line, there being present switching devices at the telephone stations for establishing circuit through the electro-magnetic mechanism thereat; and means governed by the telephone station switching mechanism serving to operate the selecting mechanism for rendering ineffective the circuit for electro-magnetic mechanism at a companion telephone station.

In witness whereof, I hereunto subscribe my name this fourth day of May A. D., 1911.

MORTON L. JOHNSON.
